UNITED STATES PATENT OFFICE.

LEON E. LA BOMBARD AND MELVIN H. SIDEBOOTHAM, OF CHELSEA, MASSACHUSETTS,
ASSIGNORS TO SPECIALTY AUTOMATIC MACHINE COMPANY, OF CHELSEA, MASSA-
CHUSETTS, A CORPORATION OF MASSACHUSETTS.

BLANK-CARRYING MECHANISM FOR BOX-FOLDING MACHINES.

Application filed September 30, 1920. Serial No. 413,841.

To all whom it may concern:

Be it known that we, LEON E. LA BOMBARD and MELVIN H. SIDEBOOTHAM, citizens of the United States, and residents of Chelsea, in the county of Suffolk and State of Massachusetts, have invented certain new and useful Improvements in Blank-Carrying Mechanism for Box-Folding Machines, of which the following is a specification.

10 This invention relates to machines for converting sheet material such as paper or card board blanks into useful articles such as boxes, or envelopes, and refers particularly to the means for ensuring progress of the material through the machine while it is being converted from flat form to or toward the form which it is to have when completed.

15 The invention has been designed for use particularly in box folding machines of the type known as "rotary" because all or most of the moving elements of the machine operate continuously and are not reciprocatory. Such a machine, for example, is illus-
20 trated in Letters Patent No. 1,346,899, granted July 20, 1920 upon an application by Leon E. La Bombard. In machines of this type the blanks are passed through the machine while supported upon a carrying belt.

25 It is important that the blanks shall not slip or turn askew while on the carrying belt for if they were to do so the product of the machine would be imperfect or spoiled. Some machines relied upon fingers or bars to hold the blanks down, but as those devices were stationary the friction between them and the upper surfaces of the moving blanks prevented accurate forwarding of the blanks. Then, as in the patent referred

30 to, upper belts travelling synchronously with the lower or carrier belt or belts were employed to hold the blanks in contact with the lower belt or belts. Such upper belts are not always satisfactory for several reasons among which are their expense, their lack of durability, and their liability to slip and fail to travel at a speed uniform with the speed of travel of the lower supporting and carrying belt or belts.

35 40 45 50 The principal object of the present invention is to provide economical, durable, and practical means for ensuring accurate

travel of sheet material that is supported by a carrying belt or belts, and that will keep the sheet material under perfect control to prevent it from turning askew or "hitching" during its travel.

With the above object in view an important feature of the invention consists in the combination with one or more carrying belts of a series of idly mounted rolls arranged in staggered or overlapping relationship and supported in position to bear continuously on the sheet material which is advanced through the machine by said belt or belts, even when such material is in the form of the smallest sizes of box blanks.

To ensure accurate and uniform travel of the blanks it is essential that there shall be no release of absolute control of any blank at any time or point during the folding operation. We attain this object by so mounting each individual roll of the series that it will bear with yielding pressure on the blanks below it.

When folding machines having upper pressing or holding belts are used to operate on blanks of heavy or stiff material, the folding instrumentalities sometimes act to shift the blanks laterally because the upper belts do not present sufficiently rigid edges to with-stand the side pressure when the outer sections of the blanks are turned up by the folders. An important feature of our invention which overcomes any tendency to such lateral shifting of the blanks consists in the provision of a series of arms or strips the lower ends of which are in alinement and present a straight guide against which the blanks are "broken" on their crease lines, said arms or strips having idly mounted rolls which bear on the blanks close to said crease lines.

The above and other features of the invention will be described hereinafter and pointed out in the claims.

Of the accompanying drawings:—

Figures 1 and 2 are, respectively, a side elevation and a perspective view of so much of a box folding machine containing our present improvements as are necessary to illustrate the invention.

Figure 3 is a detail perspective view illustrating how the roll units are hung.

Figure 4 is a diagrammatic plan view of some of the rolls illustrating their staggered relationship.

Figure 5 is a sectional view of one roll 5 and its anti-friction mounting, on lines 5-5 of Figure 1, on a larger scale.

Figure 6 is a plan view illustrating a preferred relative arrangement of all rolls so as to dispense with all upper presser or carrying belts, blanks undergoing folding operations being indicated by dotted rectangles.

Figures 7 to 12 are sectional views on lines of Figure 6 indicated by the numerals 15 7 to 12.

Figure 13 is a plan view of a creased blank with a diagrammatic illustration of how the staggered rolls bear upon it at the beginning of the folding operation.

20 A portion of the frame of a box folding machine is illustrated at 12, said machine having suitable pulleys and driving mechanism for one or more blank-supporting or carrier belts. In the present drawings we 25 illustrate two such belts at 13 and 14. Preferably said belts are positively driven by mechanism which ensures their travel at constant uniform surface speeds regardless of wear of the belts, which mechanism may 30 be such as described and claimed in our application filed May 10, 1920, Serial No. 380326. As is usual in box folding machines having two blank-carrying belts, the belts 13 and 14 are laterally adjustable to provide 35 for folding blanks of varying widths. Such structure being well known it is not necessary to illustrate means for effecting the adjustment.

40 Mounted and laterally adjustable on two cross bars 15 of the frame are two castings or brackets 16 each having ears 17 through which screw-threaded studs 18 pass vertically. Nuts 19 on the studs above and below the ears 17 provide for securing each 45 stud in desired vertical position. In other words each stud can be independently adjusted vertically and held in its adjusted position.

50 Rigidly secured to the lower ends of the front and rear studs of each bracket 16 is a plate 20, the connection being of any preferred kind such as screws 21 passed from below up through holes in the plate 20 and into the lower ends of the studs.

55 By means of screws 22 and set nuts 23 longitudinal bars 24 are secured to the under sides of the plates 20. In the machine illustrated, the plate 20 which is above belt 14 carries one bar 24 while the plate 20 which 60 is above the other belt 13 carries two bars 24, one longer than the other for a reason which will be described hereinafter in connection with Figures 6 to 12.

The upper edge of each bar 24 is formed 65 or provided with a series of notches 25 (Fig.

3) and each notch receives a cross pin or rivet 27 which connects the upper ends of two thin strips 26, the latter being also connected, at a lower point, by a cross ledge 28 between which and the lower end of a screw 22 (Fig. 1) a spring 29 is confined.

Mounted in the lower end of each pair of strips 26 is a roll 30 in position to bear on a blank borne by the belts 13, 14. For reasons hereinafter explained it is essential that the 75 rolls 30 shall revolve with the utmost freedom and that they shall be of compact construction and also present their lower peripheral portions close to the lower edges of the strips 26. As best shown in Figure 80 5, each roll consists of a ring internally grooved to form a raceway for balls 31 which ride on a hub composed of two disks 32 having laterally bevelled peripheries facing each other to form an annular track for 85 the balls. The two disks 32 are of a thickness to just fit the space between the lower ends of two strips 26 and are clamped together and to said strips by rivets 33. The disks 32 at their larger diameters are but 90 slightly smaller than the side openings in the ring or roll 30 so that the circular side crevices will be as narrow as possible and yet avoid friction between the fixed disks and the idle roll or ring 30. This structure 95 is not only strong, compact and durable but it effectually excludes dust which is an important feature in the present invention. If dirt could and did accumulate in the raceway it would interfere with the rotation of 100 the roll 30 and tend to cause blanks to turn askew since the blanks are advanced only by the friction of the belt or belts below the rolls. The structure is such that the anti-friction mounting of the rolls is maintained 105 at all times. All of the parts (which besides the rivet and balls are but three in number) are capable of being machined and therefore the structure is an economical one.

110 The simple heading up of the rivet 33 clamps all of the members of the roll and its bearing together.

The rivets 27, 33, rigidly connect the two strips 26 which constitute a frame or arm 115 for the blank-pressing roll 30, each frame or arm and its roll constituting an independent unit which may be readily hung from a bar 24 when the latter is disconnected from its supporting plate 20, or removed from said bar. It is easy to assemble the units in absolutely correct positions because they can be simply slipped onto the bars 24 and their rivets 27 dropped into the notches of the bars 24, and because the strips 26 are so spaced as to closely fit the sides 120 of the bars. They are then swung up until their ledges 28 engage the springs 29 and the bars are then connected to the plates 20.

125 Each strip 26 is in the form of a rhomboid, resulting in several advantages, viz 130

the strips can be economically cut from stock without waste, the tips of the upper acute-angled ends can be and are located so close to the under face of the plate 20 (Fig. 1) as

5 to limit downward swinging movement of the units and their rolls, and (an important feature) their lower edges can be and are so relatively located as to furnish a practically continuous folding line. In the operation 10 of the machine as hereinafter described in connection with Figs. 6 to 13, the bodies of the blanks are held firmly on the travelling belts 13, 14, while marginal or flap portions of the blanks are turned up or "broken" 15 on crease lines close to the lower edges of the right and left hand line of strips 26.

The reason for limiting downward swinging movement of the roll units is that the belts 13, 14, may not always be in position close to and under the rolls 30. A belt 20 may be out of position when repairs are being made or when lateral adjustments are being effected as is customary with most modern machines of this character. If a 25 belt 13 or 14 is so far to one side as to be out of position to support the rolls 30, the upper rear tips of the strips 26, by contacting with the plate 20, prevent the units from swinging on their pivots 27, 25 far enough 30 to permit the rolls 30 to reach a low position that would interfere with easy lateral restoration of the belt to its proper position.

In machines of this general type which cause blanks to travel with one or more 35 belts by being kept firmly in contact therewith, the blanks are folded first on one crease line and then on another parallel crease line, while traveling. So far as concerns the features of invention claimed here- 40 in, the folding instrumentalities may be of any well known approved character. In Figures 6 to 12, which are included chiefly to illustrate the reason for the staggered relationship of the rolls 30 of the three series, we indicate folding instrumentalities only 45 conventionally. Said instrumentalities as indicated comprise twisted belts 34, 35 and blank guiding blades or shoes 36, 37, in alinement with two of the series of rolls 30. We do not illustrate means for driving the 50 belts 34, 35, or for guiding their operative stretches in the proper paths, or detail supports for the members 36, 37, as such are well known and illustrated in a number of 55 Letters Patent.

The members 36, 37 may be similar to the members which serve the same purpose in the machine illustrated in our application Serial No. 380326 hereinbefore referred to, 60 one of said members having tapering rolls as claimed in that application.

By means of the studs 18 and nuts 19 each plate 20 can be adjusted accurately so as 65 to cause its roll units to coact properly with 5 the travelling blank support. That is, each

plate can be adjusted vertically and can also be slightly tilted endwise to cause the rolls at the far end thereof and the blade or shoe which is secured thereto to be in correct position relatively to the travelling support. 70

Commercially successful box folding machines are required to correctly operate on blanks of widely different shapes and sizes. Those of the smallest sizes are the ones which are the most difficult to pass through the machine without their turning askew. The tendency to turn askew occurs chiefly during the first step of folding—the first "breaking" of the blanks on their crease lines. When stationary bars have been used to hold 80 the blanks down, the friction between the blanks and such bars tends to cause twisting of the blanks. And upper belts for holding purposes have not always been satisfactory for the reasons hereinbefore explained. By 85 our present structure of yieldingly mounted rolls which bear directly upon the blanks, and by making them small enough and so mounting them in staggered relationship that even the smallest blanks will always be 90 borne upon by a plurality of rolls, pressure is always maintained at a sufficient number of points to ensure correct travel of the blanks on and with the lower belt or belts. By staggered relationship we mean 95 the relative mounting of the rolls 30 with the axes of the rolls of one series out of alinement with the axes of the rolls of the next parallel series as indicated by comparing Figures 2, 4, 6 and 13. In Figures 4 100 and 13 the axes of the rolls are indicated by dot and dash lines.

If it be assumed that Figure 4 represents the rolls 30 as of full size, and that those of each row or series carried by a bar 24 are 105 closely spaced as shown, then any blank as small as 2 inches length, which is about the smallest size ever used, will be pressed on the belts 13, 14, by the simultaneous action of five or six rolls 30. It is to be understood 110 of course that the points where the rolls 30 bear on the blanks are directly under the dot and dash axial lines in Figure 4. When longer blanks are being operated upon, a greater number of rolls bear upon it (Fig. 115 13).

Figures 4 and 13 represent a preferred number and grouping of the rolls 30 at that end of the machine which first takes control of blanks supplied by the feeder (not shown). Said end of the machine is indicated at the lower part of Figure 6, and it is here that the first breaking operation occurs (Fig. 7) and where the first tendency of a blank to be turned askew occurs. As 125 the blank proceeds there is a lesser tendency to twist or turn.

It is for the above reason, viz: prevention of tendency of a blank to turn askew as the result of the first breaking operation, 130

that we provide a plurality of pressure rolls 30 in staggered relationship bearing upon the one single belt 13. By this arrangement the blanks are held firmly while travelling so that they can not swing or turn askew even if the other belt 14 should happen to slip and travel at a speed different from the speed of belt 13.

The blanks such as A in Fig. 13 are longitudinally creased on four lines *a b c d* to cause them to consist of panels or sections *e f g h i*. The machine folds only on the lines *b* and *d*. At first each blank is under full control as indicated in Figs. 4 and 13, the lower part of Figure 6 and Figure 7, because the rolls of three rows bear upon it. As it proceeds, the left hand folders 34 turn the panels *e f* up, "breaking" the blank on line *b* (Fig. 13), and it is still under the same control until the panel *f* is turned substantially upright and the crease line *b* fully "broken." It is then in such condition that the blade or shoe 36 and the rolls of two rows will control it (Figs. 8 and 9). After passing the position indicated in Figure 9 the folder 35 begins to turn up the panel *i* and "break" the blank on crease line *d* (Figs. 10, 11 and 13) after which a lesser number of rolls 30 are needed to bear on the blank because the blades or shoes 36, 37, aided by the pressure of the belt 34 when in the positions indicated in Figs. 11 and 12, so guide the blanks that they can not turn askew.

It will be understood that in the operation of the machine as indicated in Figs. 6 to 13, the belt or belts 13, 14, constitute a travelling support for the blanks each of which, during the folding, is under the control of first three rows of rolls, then two rows, and then one row, and that during all this time each blank will be under the control of a plurality of rolls even when somewhat less than two inches long. This is when the rolls are of substantially one inch diameter and so closely arranged that their peripheries only just clear each other.

A particular advantage in the use of this machine is that unless the blanks are exceptional as to relative proportions of their panels it is possible to fold the panels *e f* completely into contact with panels *g h* while the blanks are still under the control of a number of rolls. For example, Figure 13 shows a common form of blank. The width from the edge of panel *e* to line *b* is less than from line *b* to the sides of the intermediate row of rolls and still less than the distance to the sides of the longer or right hand row of rolls. Therefore any blank of such form as in Figure 7 can be folded even to the condition shown in Figures 10 and 11 while the rolls of one or two rows are still bearing on panels *h i*. The 65 actual relative point at which the fold on

line *b* is completed depends upon the longitudinal point of the machine at which the folder belt 34 is completely deflected inwardly. We do not show the deflecting means as the same may be of any well known and commonly used adjustable type.

Having now described our invention, we claim:

1. In a machine of the character described, a single travelling support for blanks, and a plurality of longitudinal rows of pressure rolls to coact with said support in forwarding blanks, the axes of the rolls of one row being out of alignment with the axes of the rolls of the adjacent row, the said support being wider than the space occupied by the rows of rolls.
2. In a machine of the character described, a single travelling support for blanks, and a series of pressure rolls mounted to bear on said support at points in staggered relationship.
3. In a machine of the character described, a blank carrying belt, and a series of pressure rolls in positions to bear on the belt at points in staggered relationship, said belt being wider than the lateral space occupied by said staggered rolls.
4. In a machine of the character described, a single blank carrying belt, and a series of yieldingly mounted pressure rolls in positions for all to bear on the one belt at points in staggered relationship.
5. In a machine of the character described, a single blank carrying belt, and a series of anti-frictionally mounted pressure rolls in positions for all to bear on the one belt at points in staggered relationship.
6. In a machine of the character described, a single blank carrying belt, and a series of yieldingly and anti-frictionally mounted pressure rolls in positions for all to bear on the one belt at points in staggered relationship.
7. In a machine of the character described, a travelling support, means for folding blanks thereon to bring different lateral areas of the blanks into flat superposed relationship, and a plurality of independently yielding pressure rolls in position to successively bear on the blanks until said flat relationship is reached.
8. In a machine of the character described, a single travelling support, means for folding blanks thereon to bring different lateral areas of the blanks into flat superposed relationship, and a plurality of staggered pressure rolls in position to successively bear on the blanks until said flat relationship is reached, said rolls being laterally spaced at distances to enable all to bear on the single travelling support.

9. A folding machine having a pair of blank-carrier belts, folding instrumentalities for blanks on said belts, and small anti-

frictionally mounted and independently yieldable pressure rolls of uniform diameter above both belts for ensuring uniform travel of the blanks with the belts.

5 10. A folding machine having a pair of blank-carrier belts, folding instrumentalities for blanks on said belts, and small anti-frictionally mounted and independently yieldable pressure rolls of uniform diameter

10 above both belts for ensuring uniform travel of the blanks with the belts, the axes of said rolls being out of alinement with each other.

11. A folding machine having a pair of blank-carrier belts, folding instrumentalities for blanks on said belts, and a plurality of rows of small independently yieldable pressure rolls above said belts.

12. A folding machine having a pair of blank-carrier belts, folding instrumentalities for blanks on said belts, a single row of pressure rolls above one belt and two rows of pressure rolls above the other belt, said rolls being independently yieldable.

13. A folding machine having a pair of blank-carrier belts, folding instrumentalities for blanks on said belts, and three rows of independently yieldable upper pressers in position to hold the blanks under control at three lateral positions.

30 14. A folding machine having a travelling carrier, folding instrumentalities for blanks on said carrier, a row of independently yieldable pressure rolls above the carrier, and guiding means to define the line on which the blanks are folded.

15. A folding machine having a travelling carrier, folding instrumentalities for blanks on said carrier, a row of pressure rolls above the carrier, each of said rolls being independently yieldable, and guiding means to define the line on which the blanks are folded.

40 16. A folding machine having a blank-carrying belt, a bar above said belt, means for adjusting said bar toward and from the belt, and independently yieldable rolls carried by said bar.

17. A folding machine having a blank-carrying belt, a bar above said belt, rolls yieldingly connected with said bar, and means for varying the height of the bar.

18. A folding machine having a blank-carrying belt, a bar above said belt, and a series of units each comprising a frame yieldingly connected with said bar and having a roll in position to bear directly upon blanks carried by the belt.

19. A folding machine having a blank-carrying belt, a bar above said belt, and a series of roll-carrying units pivotally connected with the bar.

20. A folding machine having a blank-carrying belt, a bar above said belt, and a series of roll-carrying units each being pivotally connected with the bar and having

means for independently adjusting the degree of pressure exerted by it on blanks carried by the belt.

21. A folding machine having a blank-carrying belt, a bar above said belt, and a series of inclined roll carriers pivotally connected with the bar.

22. A folding machine having a blank-carrying belt, a bar above said belt, and a series of inclined roll carriers pivotally connected with the bar, means being provided for limiting downward movement of the rolls.

23. A folding machine having a blank-carrier, a longitudinal series of roll-carrying arms yieldingly supported above said carrier, means for varying the relative lateral positions of said carrier and arms, and means for preventing excessive movement of the rolls past the carrier if temporarily at one side thereof.

24. A folding machine having a blank-carrier, and a longitudinal series of downwardly and forwardly inclined arms pivotally supported above the carrier and having rolls at their lower ends.

25. A folding machine having a blank-carrier, and a longitudinal series of downwardly and forwardly inclined arms pivotally supported above the carrier and having rolls at their lower ends, means being provided for limiting downward swinging movements of the arms.

26. A folding machine having a blank-carrier, a bar above the carrier, and a series of downwardly and forwardly inclined arms pivotally connected with the bar and each having a roll at its lower end, each arm having a straight edge close to one side of its wall.

100 27. A folding machine having a blank-carrier, a notched bar above the carrier, and a series of inclined arms having pivot portions engaging the notches of the bar and having rolls at their lower ends.

110 28. A folding machine having a blank-carrier and a longitudinal series of roll-carrying arms pivotally mounted above the carrier, each of said arms comprising a pair of rhomboid-shaped strips between which a roll is mounted.

120 29. A folding machine having a blank-carrier, a plate rigidly supported above the carrier, and a longitudinal series of roll-carrying arms pivotally mounted below the plate, each of said arms comprising a pair of rhomboid-shaped strips between which a roll is mounted, the upper tips of said strips being adapted to coact with the under surface of the plate to determine the lowermost positions to which the arms and their rolls can swing.

125 30. A folding machine having a blank-carrier and a longitudinal series of roll-carrying arms pivotally mounted above the

carrier, the said arms having lower edge portions in alinement and having rolls closely beside said edge portions.

31. A folding machine having a pair of blank-carrier belts, a row of pressure rolls above one belt, and two rows of pressure rolls above the other belt, the three rows being of different lengths and the axes of the rolls being out of alinement.

10 32. A machine of the character described having a blank-carrying belt, folding instru-

mentalities for operating upon blanks forwarded by said belt, and a row of yieldingly mounted pressure rolls having exposed lower portions to bear directly on said belt or on ¹⁵ blanks carried thereby, said rolls being relatively mounted to ensure constant contact of each of them with either the belt or a blank.

In testimony whereof we have affixed our signatures.

LEON E. LA BOMBARD.
